UNITED STATES PATENT OFFICE.

CLAUDE M. GARLAND, OF CHICAGO, ILLINOIS.

GAS-PRODUCER.

1,115,804.

Specification of Letters Patent.

Patented Nov. 3, 1914.

Application filed December 19, 1913. Serial No. 807,611.

To all whom it may concern:

Be it known that I, CLAUDE M. GARLAND, a citizen of the United States, residing at Chicago, in the county of Cook and State of Illinois, have invented new and useful Improvements in Gas-Producers, of which the following is a clear and exact description, reference being had to the accompanying drawings.

10 My invention refers to producers of the type in which a blast of air and an endothermic reagent such as steam or carbon dioxid is passed through an incandescent bed of fuel whereby a combustible gas is generated.

15 The object of my invention is to provide a producer of this type for the gasification of bituminous fuels in which the rotation of a central section of the producer agitates the lower portion of the fuel bed to prevent the formation of clinker, and at the same time agitates the upper distillation or coking zone to prevent or break up the formation of coke.

20 A further object of my invention is to provide means for distilling off the volatile matter of bituminous fuels in such a manner as to convert a large portion of the volatile matter into fixed combustible gases instead of condensable hydrocarbons and pitch. This latter object is attained by causing non-oxidizing gases such as superheated steam or steam mixed with a portion of the gases leaving the producer to pass downward through the green bituminous fuel so that the volatile matter is distilled off at a low temperature, that is, a temperature under 900° F. This form of distillation tends to prevent the formation of coke, increases the calorific value of the gas generated and consequently raises the efficiency of the producer.

25 Further advantages will be brought out in the following description and in the accompanying drawings which form a part of this specification.

30 Referring to the drawings in which like numerals refer to the same parts in the different views: Figure 1 shows a vertical section taken through the center of my producer while Fig. 2 shows a plan view in part section taken on the line A A of Fig. 1.

35 The numeral 1 indicates an intermediate rotating gasification chamber which consists of the steel shell 6 lined with firebrick 4. Near the top is the water seal 28 and near

the bottom is the mantle ring 49 on which the fire brick lining 4 is supported. The shell 6 is riveted at 50 to 49. To the mantle ring 49 is attached the bosh plates 7 provided with perforations 51 for the admission of the blast.

35 indicates an annular rack or worm wheel which meshes with the worm 43 and which is bolted rigidly to the mantle ring 49.

44 is a track which is formed on the rack 35 and which is supported on the rollers 36 mounted on the columns 30 and 32.

3 indicates a lower stationary chamber 70 which is made up of the ash cone 24 provided with dumping valve 45 for the removal of ash, and the shell 26 which is provided with the supporting angle 25.

27 is a water seal which prevents the escape of the blast between the lower stationary chamber 3 and the intermediate rotating chamber 1.

22 indicates a fuel or ash support which is rigidly mounted on the beams 23.

21 is a blast pipe communicating with the interior of the chamber 3.

19 is a blast hood mounted on the casting 52 which forms a part of the ash support 22. 19 permits the blast to pass to the center of 85 the fuel bed while the openings 51 in the bosh plates 7 permit blast to pass to the sides of the fuel bed.

20 indicates wings cast on the casting 52 which tend to prevent the ash from slipping 90 around the casting 52 when the chamber 1 is in rotation, thus producing greater agitation in the ash around the ash support. Ash bars 33, extend over the support 22 and are rigidly mounted in bushings 34 which are 95 in turn supported from the casing or shell 26.

The numeral 29 indicates a stationary water cooled top plate. The escape of gas between the intermediate rotating chamber 100 1 and the top plate 29 is prevented by the water seal 28. The top plate 29 is formed by the dished sheet 12, top sheet 10 and side sheet 53.

11 indicates poking holes which extend 105 through the top plate.

31 indicates brackets which are rigidly mounted on the shell 53.

30 and 32 indicate columns which support the top plate 29. The column 30 is shown 110 out of its true position in Fig. 1.

The gas exit 13 is mounted on the top

plate 29 and extends therethrough. The stationary upper distillation chamber 2 is flanged at the bottom by the top plate 29.

9 is a cover plate which carries the fuel charging device 19.

8 indicates the steel shell which is lined with the fire brick 5.

The chamber 2 is smaller in diameter than the chamber 1 and is preferably made oval or oblong in section while the intermediate chamber 1 is made circular. The object of this arrangement is to prevent the fuel in the upper chamber 2 from rotating with the fuel in the intermediate chamber 1. The oblong section causes a shearing action to take place between the fuel in the two chambers which is very beneficial in breaking up any coke that may form and in causing the descent of the fuel in the chamber 2. The walls of chamber 2 are tapered to also facilitate the descent of the fuel. The chamber 2 is preferably located eccentrically with respect to the chamber 1 to make room for the gas exit 13.

14 is a pipe which communicates with the gas space in the upper part of the chamber 1 through the gas exit 13 and with the pipe 16 which in turn communicates with the space in the upper portion of the chamber 2. 15 is a valve located in the pipe 14.

17 indicates a steam nozzle extending into the pipe 16.

18 is a cut off valve in the steam line 51 which supplies the nozzle 17. By turning steam into the nozzle 17 a suction is produced in the pipe 14 which draws gas from the chamber 1 and forces it, together with the steam, into the chamber 2.

55 indicates a rotating shaft on which is rigidly mounted the eccentric 39 which operates to raise and lower the arm 40 through the rod 38. The arm 40 is loosely mounted on the shaft 48 which is journaled in the bearings 47. The worm 43 is rigidly mounted on the shaft 48.

41 is a pawl pivoted to the arm 40.

42 is a ratchet wheel rigidly mounted on the shaft 48. As the arm 40 rises and falls the pawl 41 moves the ratchet wheel 42 which rotates the shaft 48 the worm 43 and the rack 35, which causes the rotation of the chamber 1.

The operation of the producer is as follows: Fire is started in the producer in the ordinary way and coke charged through the device 19 until it is within a foot of the top of the chamber 2. The chamber 1 is now rotated through the worm 43, and bituminous fuel charged onto the coke. The blast of air and steam enters through 21, passes up through the fuel contained in 1 and generates a combustible gas which passes out through the exit 13. Steam is turned onto the nozzle 17 and passes into the chamber 2; this steam in the well known manner,

due to its velocity of discharge, tends to produce a vacuum in the pipe 14, which draws gas from the chamber 1 and this gas which should have a temperature of about 1000° F. under normal conditions, mixes with the steam thus superheating it and the mixture of gas and steam is discharged into the chamber 2 and forced downward through the green bituminous fuel. Due to the low temperature of the mixture the volatile matter in the fuel is distilled off largely in the form of fixed gases although a small amount of pitch is formed and some light oils which are readily condensable at room temperature and yield valuable by-products. The volatile matter distilled off mixes with the combustible gases from the chamber 1 and passes to the gas exit 13.

This mixture of low temperature gases and distilled volatile matter descending through the upper chamber 2, maintains the top plate 29 at the mouth of the chamber 2 cool so that it does not wear out readily. If it were not for this the high temperature from the fuel in the chamber 1, combined with the chemical action of the gases and the abrasion between the fuel and the center ring of the top plate 29 would soon destroy the center ring. As the chamber 1 rotates the large mass of fuel in the upper part tends to remain stationary and rotate with the chamber. The fuel in the chamber 2, due to the flattened section of this chamber, is prevented from rotating, this results in a direct shearing of the fuel between the two chambers, which grinds up the coke that has been formed, causes the fuel in the upper chamber to descend and stops up any holes that may form in the fuel bed in the rotating chamber 1. As the chamber 1 rotates the ash around the casting 52 is given a twisting motion which extends up into the fuel contained in 1, thus tending to prevent the formation of clinker and breaking up that which does form. During the rotation of the chamber 1 the ashes resting on the support 22 tends to follow the rotation of the chamber. In doing this they come in contact with the inclined ash bars 33 and slide along these until they are raked off into the ash cone 24 and at some convenient time dumped through the door 45.

Having thus described my invention, I claim:

1. In a gas producer having a horizontally divided casing, a top covering the upper portion of the said casing, a chamber of flattened section mounted on the said top and eccentrically thereto, and the lower portion of the said casing revolving with respect to the said upper portion substantially as described.

2. In a gas producer, a lower stationary supporting chamber, an intermediate rotating chamber, a stationary top plate mount-

- ed above the said intermediate rotating chamber, an upper chamber of smaller diameter than the other said chambers mounted on the said top plate, whereby an annular 5 gas space of triangular section is formed between the said top plate, the walls of the said intermediate rotating chamber and the fuel contained therein and a gas off-take pipe mounted on the said top plate and communicating with the said annular gas space.
3. In a gas producer, a lower stationary chamber, an intermediate rotating chamber, a stationary top plate mounted above the said intermediate rotating chamber, an upper chamber of smaller diameter than the other said chambers mounted on the said top plate, and eccentrically with respect to the said intermediate rotating chamber, whereby an annular gas space of triangular 15 section is formed in the upper part of the said intermediate rotating chamber, and a gas off-take pipe mounted on the said top plate and communicating with the said annular gas space.
- 20 4. In a gas producer, a lower stationary chamber, an intermediate rotating chamber, a stationary top plate mounted above the said intermediate rotating chamber, an upper chamber of flattened or oval section mounted on the said top plate, whereby an annular gas passage of triangular section is formed in the upper part of the said intermediate rotating chamber, and a gas off take pipe mounted on the said top plate and communicating with the said annular gas space in the upper part of the said intermediate rotating chamber.
- 25 5. In a gas producer, a lower stationary chamber, an intermediate rotating chamber, a stationary top plate mounted above the said intermediate rotating chamber, an upper chamber of flattened or oval section mounted on the said top plate and eccentrically with respect to the said intermediate rotating chamber whereby an annular gas space of triangular section is formed in the upper part of the said intermediate rotating chamber and a gas off-take pipe mounted on the said top plate and communicating with the said annular gas space.
- 30 6. In a gas producer, a lower stationary chamber, an intermediate rotating chamber, a stationary top plate mounted above the said intermediate rotating chamber, an upper chamber of flattened or oval section mounted on the said top plate and eccentrically with respect to the said intermediate rotating chamber and a gas off-take pipe mounted on the said top plate and communicating with the said annular gas space.
- 35 7. In a gas producer, a lower stationary chamber, an intermediate rotating chamber, a stationary top plate mounted above the said intermediate rotating chamber, an upper chamber of flattened or oval section mounted on the said top plate and eccentrically with respect to the said intermediate rotating chamber and a gas off-take pipe mounted on the said top plate and communicating with the said annular gas space.
- 40 8. In a gas producer having a horizontally divided casing, a top covering the upper portion of the said casing, a chamber of flattened section mounted on the said top and eccentrically thereto, the lower portion of the said casing being revoluble with respect to the said upper portion, a pipe communicating with the upper portion of the said chamber of flattened section and with the upper portion of the said horizontally divided casing, and a steam nozzle located in the said pipe and adapted to discharge steam into the upper portion of the said chamber of flattened section.
- 45 9. In testimony whereof I have signed my name to this specification in the presence of two subscribing witnesses.

CLAUDE M. GARLAND.
